UNITED STATES PATENT OFFICE

THOMAS C. VAN DEGRIFT, OF DETROIT, MICHIGAN, ASSIGNOR TO GENERAL MOTORS RESEARCH CORPORATION, OF DETROIT, MICHIGAN, A CORPORATION OF DELAWARE

FLYWHEEL BALANCING MACHINE

Application filed October 27, 1928. Serial No. 315,509.

Utilizing many of the principles that were exemplified in a crank shaft balancing machine application, S. N. 127,712, filed on or about August 6, 1926, by Caleb E. Summers 5 jointly with the present applicant, but suitable for use in perfecting any of a wide variety of rotary elements, the present invention has been designed with special reference to the rapid ascertainment and correction of 10 any unbalance in fly wheels or similar bodies having hubs.

Without implying any restriction, in actual use, to the balancing of units, such as fly wheels, whose mass may be largely concentrated in proximity to a single plane perpendicular to a geometrical axis, this machine, adapted both to the obtaining of information in regard to unbalance and to the correction thereof, will be described as provided 15 with a special and standardized "arbor", including special centering means, with means for raising and lowering said arbor, and with novel means for effecting an actual removal of ascertained amounts of material from any 20 imperfectly balanced fly wheels or other units,—such removal being effected, wholly or in greater part, while the units remain in the balancing machine and are favorably positioned for further test.

25 The mentioned material-removing means may include a special drill press organization having precision adjustment features which are believed capable of alternative uses; a novel chip-eliminator may be used therewith; and the present invention may include also the provision of novel means to facilitate the positioning, the support, and the removal of fly wheels or other units to be balanced,—the indicating means employed being either similar to or an improvement 30 upon the corresponding means disclosed in the mentioned pending application and applicable, in either case, to alternative uses in ascertaining the behavior or properties of rotating bodies.

45 Typical embodiments of this invention may comprise an electric motor and a gear box or transmission housing secured at or near the top of an upright main frame or post; and substantially parallel shafts, re-

spectively serving as a main drive or "spinning" shaft, as a cam or control shaft, as an indicator shaft, and as a drill shaft may all extend downward from said housing,—upon which a control lever may be pivotally secured. Said housing may contain an hydraulic brake and may include means for a transmission of motion from said lever to said cam shaft, means for a transmission of motion simultaneously from said motor to 55 the main drive shaft and to said indicator shaft, and means for an alternative transmission of motion to said drill shafts,—shifts being effected in such sequence as to assure rapid and reliable operation of said machine. 60

65 Other objects of this invention, aiming at a maximum accuracy of balance in a minimum of time (its means and methods being applicable to the balancing of various disc-like or other bodies) and numerous details of 70 improvement upon or addition to the balancing machine disclosed in the mentioned application, may be best appreciated from the following description of an illustrative embodiment of the present invention, taken in 75 connection with the appended claims and the accompanying drawings.

Fig. 1 is a side elevational view.

Fig. 2 is a horizontal sectional view, taken substantially as indicated by the line 2—2 80 of Fig. 1, but with parts broken away.

Fig. 3 is a partial horizontal sectional view taken substantially as indicated by the line 3—3 of Fig. 1.

Fig. 4 is a partial front elevational view, 85 taken substantially as indicated by the arrow 4 of Fig. 3.

Fig. 5 is a horizontal sectional view, taken substantially as indicated by the lines 5—5 90 of Figs. 1 and 6.

Fig. 6 is a vertical sectional view, taken substantially as indicated by line 6—6 of Fig. 5.

Fig. 7 is a general front elevational view, 95 taken as from the right of Fig. 1.

Fig. 8 is a partial horizontal sectional view, taken substantially as indicated by the line 8—8 of Fig. 7, and showing details of a preferred wobble-limiting means adapted alter- 100

natively to permit or to prevent eccentric movement or wobbling of an arbor or a like central element during the rotation thereof.

Fig. 9 is a vertical sectional view, taken substantially as indicated by the line 9—9 of Fig. 8.

Fig. 10 is a partial side view, taken substantially as indicated by the arrow 10 of Fig. 7, and showing only a control lever and associated parts.

Fig. 11 is, for the most part, a vertical sectional view of a main "spinning" shaft, this view being taken substantially as indicated by the arrow 11 of Fig. 1, with parts broken away.

Figs. 12 and 13 are respectively, a horizontal section taken substantially as indicated by the line 12—12 of Fig. 13 and the line 13—13 of Fig. 12.

Fig. 14 is a detail elevational view taken substantially as indicated by the arrow 14 of Fig. 13.

Fig. 15 is a separate elevational and diagrammatic view of a cam or control shaft manipulable by the lever which is separately illustrated in Fig. 10.

Figs. 16—21 are, respectively, plan views of various cams with which the cam shaft shown in Fig. 15 may be provided.

Fig. 22 is an elevational detail view, with parts broken away to a median plane, showing a preferred type of adjustable bearing for a drill stem, as hereinafter described, this view being taken substantially in the broken plane 22—22 of Fig. 23.

Fig. 23 is a top plan view separately showing that main bearing element which is disclosed also in Fig. 22.

Fig. 24 is a partial sectional view taken substantially as indicated by the line 24—24, Fig. 1, showing, in plan, certain features of drill press construction.

Fig. 25 is a detail view taken substantially as indicated by the line 25—25 of Fig. 3.

Fig. 26 and 27 are respectively a side elevational view, with parts broken away, and a front elevational view of a preferred type of indicator mechanism.

Figs. 28, 29, 30 are respectively a top plan view, a longitudinal section and a transverse section of a preferred type of chip remover, adapted to be used in conjunction with the mentioned drill.

55 General construction

Although, as in the case of the now known and publicly used balancing machine described in the mentioned application, the body to be tested and/or corrected might have its axis disposed in any desired direction, a base 20 (preferably provided with leveling screws, as suggested at 19, 19', Figs. 1 and 2) is herein shown as forwardly carrying a work-support in the form of housing 21, of somewhat

complex character, and as rearwardly supporting a cast post or special column 22,—the latter being surmounted by a rearwardly disposed motor bracket 23 and by a forwardly disposed bracket 24, carrying a gear box or transmission housing 25; and one of the mentioned brackets may have an indicator drive housing 26 supported therefrom,—all of the mentioned parts being disposed favorably to the rotation of fly wheels or other work units 70 W upon vertical axes while carried by suitable parts positioned between said work support and said box.

From the housing 26, a guard tube 27, protecting an indicator shaft 27', may extend 80 downward to any suitable indicator organization 28,—the latter being shown as also supported from post 22; and not only a main or "work-spinning" shaft 29 (preferably including universal joints 30, 30') to impart 85 rotation to any work W, but a cam or control shaft 31 and a drill shaft 32 are shown as extending downward from the gear box 25,—said drill shaft being vertically adjustable 90 through means carried by a guide block 95 mounted upon the post 22.

A main control lever 34 is shown as pivoted at 35 upon the gear box 25; and said box is shown in Fig. 5 as provided, in its front and rear surfaces respectively, with bearings 36, 37 (protected respectively by a cap 38 and a gland 39) for a horizontal shaft 40,—this shaft being directly or indirectly driven from a motor 41, carried by the bracket 23 and adapted, by means hereinafter described in detail, either to impart rotation simultaneously to indicator shaft 27 and to main shaft 29 or (upon a shifting of lever 34 and a consequent discontinuance of rotation of shaft 29) to energize the drill shaft 32,—the latter being positioned favorably to the removal of an indicated quantity of material from an indicated portion of the periphery of the fly wheel or other work W.

Through means hereinafter described, manipulation of a work-positioning handle in the form of a forwardly projecting arm 42 may operate means which assist in an initial positioning of, and/or in the support of, the work W above the block 21; a standardized arbor 43, preferably provided with some suitable means for supporting from below and very accurately centering any work W thereon, may be raised, subject to an interlocking control, relatively to the main shaft 29, by or upon a manipulation of a jack-operating lever 44; and the raising and lowering of drill point 45, conditionally rotated by shaft 32, may be accomplished by manipulation of an additional lever or drill-advancing bar 46; but a complete explanation of these successive operations, and of the preferred means of assuring their proper sequence and performance, may best follow a somewhat detailed recita- 115

tion of typical mechanisms by which said operations may be satisfactorily effected.

Work positioning and non-rotary supporting means

- 5 As suggested in Fig. 7, conveying or roller-carrying tables T, T', may advantageously be so disposed, at the sides of the balancing machine herein described, as to obviate 10 manual lifting in the transfer of fly wheels W thereto or therefrom; and the block 21, shown as comprising a substantially cylindrical lower section 21a and a rectangular upper section 21b, may be provided with not 15 only a comparatively large central opening 47 (through which the standardized armor 43 can be raised and lowered) and with an annular cam plates 48, manipulable by the arm 42, but with any desired set of rollers 20 49,—the latter being shown as disposed at substantially the same level as similar rollers 49a and 49b carried by conveyor tables T, T'. Although preferably so shaped as to bring 25 its free end to a desired level above a slot 50 through which it extends, the arm 42, shown as secured to cam plate 48 by a bracket 42'', is not intended to serve as an ordinary 30 crank, being designed, by causing an engagement of cams 51, 51' with pins 53, 53' (upon the shifting of said arm toward the right) to elevate work-stopping and centering pawls or dogs 52, 52', or (upon a shifting of said 35 handle toward the left, in preparation for a drilling operation which occurs, if at all, only after intervening operations) to cause 40 engagement of cam surfaces 54 with rollers 55, and thereby to elevate work-levelers of platen elements 56,—the dogs 52, 52' and the work-levelers 56 being otherwise depressed 45 (during "spinning" operations and handling operations) below the tops of rollers 49,—as by means of springs, 57, 58, surrounding interposed slidable elements 59, 60 of said pins and said work-levelers.
- 50 As more fully detailed below, the dogs 52, 52' and work-levelers 56 are constructed and disposed with special reference to diameter and configuration of the work W and to its adequate support,—one or all of said work-levelers serving as a press plate or platen, during such drilling operations, if any, as may be deemed requisite in view of observations of indicator 28, as made during a "spinning" which precedes the elevation of 55 said work-levelers.

Arbor elevator or jack

- 59 Regardless of the specific construction of the means, if any, employed to facilitate the 60 positioning of work units W, assuming that said units are not provided with integral shafts, suitable means, operated or controlled by the lever 44, may be employed to manipulate a standardized arbor 43, or its equivalent, 65 relatively thereto,—the illustrated arbor be-

ing shown as provided not only with a centering organization 61, adapted to fit within a fly wheel opening, or the like, but with roller-engageable sections 62, 63, respectively disposed above and below said centering organization, with a torque-transmitting head or chuck 63, for connection with the main shaft 29, and with a tapered lower end 64, adapted to be held by, but easily removable from, some interfitting and vertically 70 slideable socket member 65, comprised in an elevating organization controlled by said lever.

For example, in view of the recognized facility of control of hydraulic and especially 80 of pneumatic devices, a valve 66, manipulable from lever 44 by means such as a link 67 and a valve arm 68, may be used to control admission of air (according as said lever is elevated or depressed) from a pressure pipe 85 69, to act upon one or the other of opposite sides of a piston (not shown) movable within a Ross air cylinder 70, or the like, and connected with a slidable rod 71.

In preference to disposing the air-manipulable rod 71 vertically and directly below the arbor-receiving socket member 65, space 90 may be saved by providing the cylinder 70 with such securing means (not shown in full detail) as to permit of some longitudinal 95 adjustment thereof, and fixing a frame 72 above a suitable well 73 in a bottom section 20a of base 20; and transmission means, subject to an interlocking control, may be so employed in connection with rod 71 and frame 72 as to provide for the manipulation of arbor socket 64,—to raise the same 100 when a work unit W has been approximately positioned and to lower the same (to a level 105 favorable to the horizontal removal and reception of units W) after the requirements of accurate balancing have been ascertained and/or met. For example, an upper or main section 20b of the base 20 being shown as 110 provided with a lateral opening 74 (illustrated in Fig. 7 as provided with a door 75 having a knob 76) the frame 72 may be adapted to carry not only a gear 77, engageable by a rack 78 on rod 71, and a sprocket 79 115 driven from gear 77 by gear 80 (shafts 81 and 82 being shown as parallel) but also an upper sprocket 83, mounted upon a separate bracket 84,—which may be retained by shoulders 85, although subject to an adjusting screw 86; and a suitable chain 87, extending over the sprockets 79 and 83, may carry not 120 only a socket-receiving bracket 88 but also any desired counter weight 89.

The frame 72 is shown as carrying also a 125 bracket 90, to guide an interlocking pin 91, whose retraction from engagement with socket-receiving bracket 88 (in such manner as to permit initial elevation of said socket and bracket, together with the mentioned ar-

bor) may be dependent upon the position of a jack-interlocking cam 92 upon the control or cam shaft 31; and it may have been noted, in connection with Figs. 3 and 4, that a slide-
5 able pin 93 is so shaped and positioned as to render the vertical manipulation of the air valve rod or link 67 by lever 44 or its equivalent (a pin-and-slot being suggested at 94, Fig. 1) dependent upon a specific ro-
10 tative position of a cam 95,—shown as se-
cured on said control shaft at some distance above a lower bearing 96. Said control shaft may carry also interlocking cams 97a, 97b,—
15 the shapes and positions and relationships thereof to pins 97a', 97b' being such as to ren-
der manipulation of arm 42, to rotate cam plate 48, conditional upon a specific position-
10 of shaft 31, or vice versa; but the full significance of the control features last re-
ferred to may be best understood in connec-
20 tion with a statement of operations herein-
after provided.

It will be understood that the depth of the well 73 and the proportions of the mentioned
25 parts are intended to be such as to adapt any standardized arbor 43, whatever may be the details of its structure, to be depressed be-
low the level of the rollers 49 both during an initial work-receiving period (wherein the
30 dogs 52, 52' are so elevated as to aid in the correct positioning a work unit W) and dur-
ing a final work-removal period; that the length and the range of vertical movement of the arbor 43 are intended to be such as to fa-
35 cilitate the coupling of the same, when a work unit has been centered and secured thereon, to the main or "spinning" shaft 29; that the range of movement and spacing of the work-levers 56 is intended to be such as
40 to adapt the latter to be elevated, by means such as the rollers 49, at least during any de-
sired material-removing operations in which one or more thereof may serve as a press-
45 plate or platen; and that the dogs 52, 52' and the levelers 56 are alike held depressed during "spinning" operations, executed for the ascertaining of any unbalance; but it will be obvious that various changes in design
50 may be found advantageous in adapting this machine to the balancing of fly wheels or other work units W of special design or cast integral with shafts.

Cam or control shaft

55 Shaft 31 may be provided, externally of the gear box 25, not only with the mentioned jack-interlocking cam 92, air-valve inter-
locking cam 95 and/or cam plate interlocking 97a, 97b but with a pair of so-called lower-
60 plate or arbor-steadying cams 98a, 98b and with a similar pair of upper-plate or arbor-
steadying cams 99a, 99b,—said lower-plate cams being best shown in Figs. 1, 15, and 17,
65 and said upper-plate cams (concealed in Fig.
1 by an upper plate-carrying or feeler-carry-

ing bracket 100) being best shown in Figs. 8, 9, 15, and 20.

The cam shaft or control shaft 31 is shown in Fig. 5 and 6 as provided, within the gear box 25, with a brake-operating cam 101 and with clutch-operating cams 102a, 102b; and also with a bevel gear 103,—preferably disposed immediately above or below a two-part bearing arm comprising a flanged main element 104a and a complemental element 104b, retained by means of bolts or screws 105. The lever 34 constitutes, as indicated, a preferred means to impart successive movements of partial rotation, in one direction or the other, to the control shaft 31 or its equivalent. This may be effected by means comprising a gear sector 106, mounted upon a horizontal rock-shaft 107 and an arm, secured upon shaft 107, a link 109 being used to connect said shaft to said lever; but attention may next be directed to the power-driven parts of the main organization and to preferred means of control therefor through the mentioned cams on shaft 31.

Gear box and main drive

Referring now more particularly to Figs. 5 and 6, the shaft 40 of the motor 41, mentioned as supported by bearings 36 and 37, may be constantly rotated in the direction suggested by arrow 110; and said shaft 40 is shown as carrying not only a main clutch block 111 but worms 112 and 113 upon respective counterpart clutch blocks 114 and 115,—the clutch block 111 being slidable and shown as provided with an intermediate fork-receiving groove or channel 116. The upper end of drill shaft 32 is shown as provided with a gear 117 engaged by an idler 119, on a short shaft 118,—said idler being interlocked or rigidly connected with a worm gear 120. The latter may be in constant mesh with the worm 112; and the worm 113 may similarly remain constantly in mesh with both a gear 121 (upon an upper end or section 29' of the main "work-spinning" shaft 29) and with an additional gear 122,—the gear 122 being shown as mounted upon a short vertical shaft 123, carrying a small bevel gear 124 and as adapted, through the intermediation of a shaft 125, provided with beveled gears 126 and 127, conditionally to impart rotation to a gear 128. The latter may be so secured upon the upper end of the mentioned indicator shaft 27' as to permit of an initial rotation and adjustment, to compensate for some lag in the action of "feeler" and indicator elements, hereinafter referred to.

Clutch, brake, and gear-box lubrication

The clutch block 111 is shown as shiftable to and from an intermediate position of complete disengagement by means of a clutch lever 129, this lever being pivoted upon a stub shaft or bolt 130 and comprising fork arms 130

131, 131' (engaging in the clutch-groove 116 in the clutch block 111) and also a cam roller arm 132,—the latter being engageable by the mentioned cams 102a, 102b on shaft 31; a brake-control lever 133, pivoted at 134, may be provided with a roller or equivalent member 135, adapted to co-operate with brake cam 101; the shaft 125 is shown as carried by a bearing plate 136 (optionally integral with the housing 26) and by a bearing arm 137,—said plate and said arm being both supported from box 25; and one of the shafts 29, 123, or 125 may advantageously be provided with a brake of some suitable type,—manipulable through the mentioned cam 101 and lever 133. For example, incidentally providing means for the circulation of a lubricant reaching to a predetermined level within the gear box 35, a gear pump which comprises gears 138, 138' and a fixed pump body element 139 (shown as integral with a bearing-and-closure plate 140, supporting bearings 141 and a cap 142) may be employed for a braking effect,—gear 138 being shown as compelled by lugs 143' to rotate with shaft 123.

Assuming the gear box 25 normally to contain lubricating oil up to some such level as that roughly indicated by the line 144, Fig. 6, the described pump, or its equivalent, may be provided with a submerged inlet connection 145,—shown as equipped with a strainer 146; and an outlet pipe 147, 147', leading from said pump, may be provided with a valve 148,—capable of being opened, through the agency of cam 101 and brake lever 133, by means such as a link 149, engaging a valve-operating arm 150; a remoter portion 147' of the mentioned pipe may be provided with any desired branches,—such as are suggested at 151 and 151', Fig. 5, for the delivery of lubricant to the various mentioned bearings whenever the valve 148 is opened and the worm 133, or its equivalent, is rotated; and, to determine a maximum braking pressure, a relief valve (not shown) may be suitably inserted in pipe 147', or its equivalent.

Optional swinging support for drill shaft

To avoid unduly complicating Fig. 5, but few parts of a complete lubricating system are therein shown; and a like consideration has excluded from said figure the details of a special bearing construction preferred for use at the upper end of drill shaft 32. It is nevertheless thought proper, calling attention to dotted line 152 in said figure as indicating an optional arcuate opening, hereto comment that the retention of lubricating oil in box 25, or its equivalent, is not incompatible with the use of means permitting such adjustment of the drill shaft 32 relatively to the idler shaft 118 (as a center of rotative adjustment) and to the main or "spinning" shaft section 29' as to permit a removal of material, by rota-

tion of said drill shaft, at various radial distances from an axis of rotation common to the last-mentioned shaft and the arbor 43 and any work W thereon,—as may be advantageous in balancing fly wheels, or the like, having different diameters; but preferred details of the construction here referred to may be best understood from Figs. 22 and 23.

As shown in the figures last referred to, a special bearing element 153 may be pivoted upon idler shaft 118, or upon a bearing sleeve 154 provided therefor, and may thereby guide (at a uniform lateral distance from shaft 118 but at a variable distance from shaft 29, etc.) the drill shaft 32.

That portion of the bottom of box 25 through which drill shaft 32 extends, or a plate secured to said box, may be provided with a flat inner or upper surface 155, and optionally also with a bearing element such as the mentioned bearing sleeve 154,—the latter being adapted to constitute or to support the short shaft 118, mentioned as carrying idler 119 and worm 120; and the special bearing element 153 is shown as comprising not only a plate 157, having a co-operating flat and smooth lower surface and provided with arcuate slots 158, 159 (adapted to receive clamping screws or bolts 160) and a circular opening 161 for shaft 32, but also parallel cylindrical bodies 162 and 163,—the latter being adapted respectively to receive a sleeve containing shaft 118, and a bearing organization 164 for the drill shaft 32. Idler 119 and worm gear 120 are shown as interlocked but nevertheless freely rotatable together relatively to shaft 118; gear 117 is shown as keyed to drill shaft 32; and glands 165, 165' are shown as respectively surrounding the cam shaft 31 (Fig. 6) and shaft 32; but many of the foregoing details are here included only for the sake of completeness, being entirely optional.

Work-spinning shaft and arbor

100

105

110

115

120

125

The "work-spinning" or main shaft 29, above referred to as comprising the upper section 29', within the box 25, universal joints 30, 30', and torque-transmitting head 63, is shown in Figs. 1 and 11 as including a scale-carrying section 164, between the section 29' and the upper universal joint 30,—the universals 30 and 30' being respectively separable, upon withdrawal of taper pins 165a and 165a' and 165', from sections 29a and 29b; and the arbor-receiving head 63 may be substantially similar to that shown in the mentioned prior application,—its construction adapting it to be tightened or loosened by rotation of a collar 166.

Complete separation of the sections 29a, 29b may be obviated by means such as a head 167, optionally adjustable, adapted to engage a shoulder or other internal stop 168; and it

130

is obviously convenient, providing a fixed pointer 169, to graduate in degrees a co-operating scale 170, on section 164. In this connection, anticipating somewhat, it may be explained that whatever may happen to be the position of any work W as initially disposed upon the supporting block 21 (assuming the pointer 169 to have been previously brought opposite the zero of the mentioned scale) 10 that position may thereafter be taken as a position of reference. Thus any desired angular adjustment of a fly-wheel may be effected, after a "spinning" indication of unbalance and in preparation of a drilling operation, by manually grasping and so rotating the work W, and parts movable therewith, as to shift the scale 170 consistently with a reading previously given by the indicator 28, or its equivalent, during the "spinning" operation; but the capabilities here referred to may be best understood in connection with preferred details of construction of the arbor 43,—adapted both the center and rotatably to connect any work W with the shaft 29, or its equivalent.

Work-centering arbor construction

In connection with Figs. 12-14 inclusive, it should be recalled that separate roller-engaging arbor sections, such as that shown at 30 62 as comprising an accurately fitting and hardened shell retained upon a main arbor body element 171 by means of threaded collars 172, 173, are preferably provided both above and below the work-centering organization 61 of the arbor 43; and said work-centering organization may include a replaceable work-carrying element 174, comprising a cylindrical part 174' and a flange 174'',—the outside diameter of said cylindrical part being preferably but slightly larger than the shaft-opening in the hub of any wheel or work W that may be carried and "spun" thereby. This flanged element 174 is shown as retained between a shoulder 175 and a threaded collar 176 and as provided with laterally extending apertures 177 for work-centering pins 178. The apertures 177 may coincide with corresponding apertures 177' in the arbor body 171; and said body is shown as provided with a longitudinal bore 179, containing a pin-advancing conical cam 180, formed of hard material. 45 The pins 178, also accurately formed of hard material and shown as having rounded ends, are intended to be very exactly equal to one another in length; and they may be retained against accidental loss by means such as balls 181, adapted to engage channels 182 in said pins,—said balls being shown as resiliently pressed thereto by means of springs 183 retained in bores 184 by plugs 185; the pin-advance cone 180 is shown as movable by a stem 186, provided with guide sections 187, 188, 189,—which are intended

accurately to fit within the bore 179 or within special guides 190, 191, suitably positioned therein; and the stem 186 may be manipulated, to advance and retract the cone 180, by means such as a threaded body 192, seated in the main body 171 and shown as provided with a milled head 193,—said body preferably so receiving a stud 194, on stem 186, as to advance or retract the same, according to the direction of rotation of said body by means such as said milled head. Subject to the action of a hold-down pin 194a, advanced by a spring 194b, the stud 194 may have a limited vertical play within a chamber 194c, to obviate danger of any "binding" of mentioned parts. 70 75 80

It has been indicated that there is intended to be some lateral clearance between the work-carrying element 174 and any work W disposed thereon, and that pins 178, or their equivalent, are intended for a centering rather than a supporting effect. To adapt the flange 174 to the supporting purpose referred to, and in view of common imperfections in the hubs of fly wheels and the like, point-to-point supports therefor may be provided upon said flange,—as by the insertion and careful grinding, preferably in place, of suitable hard studs 195; and said flange may, if desired, be provided with vertically slidable and resiliently supported additional elements, such as pins 196, respectively movable by leaf springs 197,—said pins being capable of serving, *inter alia*, to guard the studs 195, to function as clutch elements and/or to facilitate the removal of any work unit W when operations thereon are completed. 85 90 95 100

As in the former instance referred to, the chuck or head 63, on the lower end of spinning shaft 29, is shown as provided with a dog or dogs 198,—advanced by rotation of a cam element or elements 199, optionally integral with a milled or other collar 166; an upper portion of the arbor body 171 is shown as provided with dog-receiving slots 201; and it will be understood that the concavity 202 within the chuck 62 or its equivalent is intended to be such that, when a work unit W has been duly centered by adjustment of the milled head 193, said head and parts immediately therebelow may all be received within said chuck,—in readiness for both a "spinning" operation (upon a lowering of the mentioned dogs 53) and any subsequent drilling or other metal-removing or metal-adding operations (executed upon a subsequent elevation of the work levelers 56) as may be required to assure the desired perfection of balance. 105 110 115 120 125

Means having the indicated general character being preferably employed to center the work W upon any arbor 42 in readiness for "spinning" and for subsequent operations effected by proper manipulation of the lever 130

34, the arbor-centering or restraining and/or "feeling" and indicating means used therewith may be either quite different from or generically similar to corresponding means 5 illustrated in the mentioned prior application,—improved but similar means being herein described.

Arbor-restraining and "feeling" means

10 It should be understood that arbor 43 preferably extends, as shown, not only through the mentioned upper plate-carrying bracket 100, shown as integral with a so-called "upper plate" which is suitable to the support of 15 such arbor-restraining and "feeling" means as are shown in Figs. 8 and 9, but also through a so-called "lower plate" 100',—the latter being preferably supported directly by the base section 20b; but the lower arbor-restraining 20 organization, controlled through cams 98a and 98b on shaft 31, may be so entirely similar in principle and in mode of manipulation to that shown in Figs. 8 and 9 as to require no 25 separate illustration,—the expediency of providing a separate "feeling" arm in connection with said lower arbor-restraining organization naturally depending somewhat upon the distribution of mass in the work units W constituting a particular batch to be tested 30 and/or balanced.

Bracket 100 will be seen to comprise, in addition to a rugged back or attachment section 100a and vertically-extending, forwardly-diminishing side webs 100b, the irregularly rounded area referred to as "upper plate" 100c; and the latter is shown as provided not only with an ample central opening 204, for the upper roller-engageable section 62 of arbor 43, but with an arcuate opening 205 for drill shaft 32 or a downward extension thereof, with an opening for cam or control shaft 31, and with additional openings corresponding to hollow trunnions or bearing sleeves 206, 207, 208. The latter are 45 accurately made, to serve as or to carry pivots for both a lower set of roller-carrying arms 206a, 207a, 208a, and a corresponding upper set of arms 206b, 207b, 208b,—said upper arms being shown as respectively provided 50 with gear sectors 206c, 207c, 208c, all engaging an identical ring gear 209; and one of the mentioned sector-carrying arms is shown as having associated therewith a control arm 210, carrying cam rollers 211, 212, for engagement by the cam or cams 99a, 99b, upon the control shaft 31. Rollers 206d, 207d, 208d, upon arms 206a, 207a, 208a (preferably chrome-plated to resist wear) are adapted to engage section 62 of arbor 43 (which may 60 be similarly plated); and precise adjustment of the control arm 210 may be effected by means such as screw 213, 213', shown as threaded into an extension 214 of arm 208b and as adapted to engage a suitable abutment 65 such as a clamping screw 219, upon arm 210.

Upper arms 206b, 207b, 208b may be integral with outer bearing elements 206e, 207e, 208e, respectively rotatable upon bearing sleeves 206, etc.; lower arms 206a, 207a, 208a may be separately carried by pivot bolts 206f, 207f, 208f; rotatable within said bearing sleeves; and resilient means such as adjustable tension springs may tend constantly to draw the rollers 206d, 207d, 208d together. Plate 100c being provided with additional 70 openings 206g, 207g, 208g, the movement or play permitted to said lower arms relatively to corresponding upper arms may be varied by means such as oppositely extending pairs of screws 206h, 207h, 208h co-operating with lugs or studs 206i, 207i, 208i,—it being relatively immaterial, except as to convenience of access, whether said studs (shown as provided with flat lateral faces, relatively inclined) are carried by the lower arms, as shown, or 80 vice versa.

The various relationships and adjustments above referred to will be understood to be such that a suitable partial rotation of the control shaft 31, as effected by means such as the lever 34, may cause the rollers 206d, 207d, 208d, either uniformly to close in upon and to steady one end of the arbor 43, during its rotation, or to so release the same as to permit such separate movement thereof as may 90 result from any unbalance,—the latter condition prevailing during the use of said rollers as parts of a "feeler" organization.

In order to adapt the mentioned roller-carrying arms to operate the indicator 28, or its equivalent, the arm 208a, for example, may be rigidly or otherwise connected with an indicator-actuating arm 215; and, all of the arms 206a, 207a, 208a, being capable of rocking movement within the limits permitted by 100 adjustment of screws 206h, 207h, 208h and by the rotative position of cams 109a, 109b, said rollers may function, at times, as "sensory" parts of a "feeling" or pressure-responsive system adapted to respond to "wabbling" of arbor 43 and to transmit motion to 105 interior parts of the indicator 28, or its equivalent.

Rollers 206d, 207d, 208d, are shown as yieldably drawn inward by resilient means 110 in the form of tension springs 206j, 207j, 208j, adjustable by screws 206k, and 207k, and 208k extending through threaded bodies 206l, 207l, and 208l, the screws 206k, and 207k being provided with milled or knurled heads 206m and 207m. Plate 100c may be additionally apertured, as at 206n, 207n, and 208n; and some or all roller-carrying arms may be provided with damping means extending thereto. This is herein done by additionally and yieldably connecting each lower arm with the arm thereabove by one of three offset fingers 206p, 207p, 208p,—the mentioned damping elements being so interposed that, although 115 pressure impulses due to eccentric motion

or "wabbling" of arbor 43, or to like cause, may be reliably transmitted therethrough, said rollers shall not otherwise vibrate or "chatter".

5 The fingers 206p, 207p, 208p are shown as respectively integral with additional arms 206b', 207b', 208b', disposed at fixed angles relatively to arms 206b, 207b, 208b; and damping organizations in the form of rubber 10 blocks 206q, 207q, 208q are shown as so interposed between fingers 206p, 207p, 208p (respectively carrying sockets 206r, 207r, and 208r, through which extend clamping bolts 206s, 207s, 208s) and correspondingly roller-carrying arms 206a, 207a, 208a (carrying sockets 206r', 207r', 208r', through which extend clamping bolts 206s', 207s', 208s') that, although the arms 206b', 207b', 208b' are compelled to move equally (because 15 20 geared together in the described manner) the rollers 206d, 207d, 208d are not restricted to synchronous and/or equal movement. Drawn inward by springs 206g, 207g, 208g, it will be seen that rollers 206a, 207a, and 208a are 20 so related that any outward pressure applied to (say) roller 208a (by reason of e. g., any tendency of shell 62 or arbor 43 to move as an eccentric) may not only swing the actuating arm 215 backward, to a corresponding degree, but may also tend, through damping 30 element 208g, arm 208b', arm 208b, gear sector 208c, ring gear 204, and parts movable by said gear, simultaneously and yieldably to apply additional inward pressure to rollers 35 206b and 207b,—assuring the retention of the same in "non-chattering" contact with arbor shell 62, or its equivalent. It is, however, for a locking effect that gears are here used.

A substantially circular and suitably apertured removable cover plate 100d, adapted to engage a machined area 100e at the edge of plate 100c, may protect mentioned movable parts; and, to facilitate adjustment of screw 208k, or its equivalent (whether employed 40 45 primarily to predetermine the pressure of application of roller 208a or as a means of zero-setting or zero-correcting the indicator-actuating arm 215, or for both of these purposes) an extension of said screw, shown as 50 55 rotatable in bearing elements in 216 and 100f, may be provided with an accessible handle or head 217.

When the mentioned parts are in proper proportion and adjustment, assuming that, 55 for example, some net excess of material at an angular distance of 25° from an assumed zero (said zero optionally corresponding to that radial plane of a fly-wheel W which passes through drill 45 as said wheel may 60 happen to be disposed when the scale 170, or its equivalent, reads zero) the consequent tendency of arbor 43, when rotating as an eccentric, to press upon the roller 208a once during each revolution may be used in so 65 operating any properly constructed indicator

28 that the readings of the latter reveal both where and how much material must be removed from the "heavy" side of the work W in order to obtain substantial perfection of balance; and one improved type of indicator 70 will accordingly be next described. In this connection it may be pointed out that the line of application of what may be referred to as maximum wobble-pressure lies, when instrumental constants are properly compensated 75 and operations are conducted at an optimum R. P. M., about opposite (i. e. at about 180° from) any net excess of mass in the work W,—said excess being initially assumed to lie in, or very near, a central horizontal plane. In the suggested case, the crest of the "wave" of lateral pressure may thus come at an angle of 105° from the assumed zero of the fly wheel; but the connections and adjustment of the indicator 28 may nevertheless be such as to give the reading "25°" 80 upon the indicator 28,—this being the position to which scale 170 should be brought in order to bring the "heavy" part of the work W directly under the drill 45, or its equivalent. 85 90

Indicator structure and operation

Indicator 28, or its equivalent, may be supported wholly or in major part by means 95 such as a bracket 218,—shown as carried by post 22 and as adapted to serve as a support for gearing whereby suitable rotation may be imparted to a mirror or set of mirrors 219, comprised in said indicator.

When intended to be used as herein described, the indicator 28 may comprise, within a housing 220, not only the mentioned rotating mirror (whose sides or faces may correspond in number with a speed-reduction 105 ratio between shafts 29 and 27'—this mirror being octagonal in cross-section) but also an oscillable concave mirror 221 (movable by any suitable indicator-actuating element 215) a light source 222, and an arcuate window 110 opening 223 having therein suitable particylindrical graph-receiving or graph-displaying translucent element 224,—a ray-restrictive element 225 and a background illumination window containing color-diffusion 115 screen 226 being optionally provided in or carried by an inner wall or walls 228, defining a lamp compartment 229.

The curvature of the oscillable mirror 221 is preferably such that an unvarying ray 120 which it receives through an aperture 230 in the ray-restrictive element 225 (shown as retained in an adjusted position by a slotted plate 231 and clamping screws 232) shall be approximately focused, as reflected from the 125 rotating mirror 219, in the plane of the graph-displaying element 224,—this being secured at a uniform radial distance from the axis of rotation of mirror 219 and of such extent as to receive a straight or curved line of light, 130

corresponding, as to the period involved in its production, with a single revolution of the shaft 29, or with a single cycle in the movement of the arm 215, or equivalent elements.

The lamp 222 may be rendered adjustable 5 in any desired planes by means such as threaded elements 233, 233', 234, adapted to serve as set screws and/or to extend through slots such as that shown at 235 in a bracket 235'. A door or pivotally supported section 10 236 of housing 220, optionally mounted upon hinges 237 at or near the center of the back of said housing, may provide for easy access to the lamp compartment and mentioned elements therein; and said compartment may be 15 provided with any desired heat-escape or ventilating means,—such as, for example, a "stack" 238, shown as provided with a screen 239.

Pivottally to support the oscillable mirror 221 for movement in a plane such as to assure continuous reflection from one or another of the reflecting surfaces of mirror 219 during each complete revolution of a "spinning" shaft 29 and any work W thereon, and to render the oscillable mirror 221 directly responsive to movements of some shiftable element such as arm 215 of a "feeling" organization, a forward extension 240 of housing 220 being 25 shown as interiorly provided with a shelf 241, apertured at 242, a removable frame 243, is shown as interfitting within the aperture 242 and as carrying not only an inclined mirror shaft 244 for mirror 221 but a vertical 30 transmission shaft 245,—said shafts being interconnected by means of light and equal or unequal gears or gear sectors 246, 247, and said transmission shaft being equipped with an adjustably carried roller-tipped multiplication lever or finger 248. A ball or roller 35 40 45 50 55 60 65 70 75 80 85 90 95 100 105 110 115 120 125 130 249 upon said finger may be retained in constant engagement with a suitable cam surface 215', near the end of arm 215, or upon any element used to transmit the movements that are to be observed, by means such as a spring 250. Said spring is shown as engaging a lower horizontal element 251 of frame 243 and a mirror-receiving block 252; and a desired initial setting may be facilitated by means such as set screws 253, 254, 255, and 256.

The cam surface 215' is shown as having associated therewith an extension surface 215''; but the latter is not intended to contact with the roller 249, or its equivalent, during "spinning" or indicating operations,—being designed merely to prevent disengagement of mentioned parts during any periods wherein the arm 215, or its equivalent, is backwardly shifted to an inoperative position, during some non-indicating operation. For example, the roller 249 may contact with the extension surface 215'' when the rollers 106d, 107d, 108d, instead of serving as "feeler" elements, are locked in their outer position, in

order to allow for advancing therethrough one end of arbor 43, or its equivalent.

To facilitate insertion and removal of the rotating mirror 219 and/or the oscillating mirror frame 243 and parts carried thereby, 70 an upper portion 257 of the indicator housing extension 240 may be separately formed and removable (as, upon the withdrawal of screws 258, shown as entering shelf 241); and the rotating mirror 219 may be provided at 75 its inner end with an interfitting part of a torque-transmitting coupling comprising elements 259 and 260,—the outer end of said mirror, or the shaft thereof, being shown as provided with a concave bearing element 261, engageable by a spring-pressed bearing cone 262 which is slidably retained within a suitable thimble 263. Chromium plated stellite is regarded as superior to steel for use in providing a true, high reflective and permanent 80 mirror 219; mentioned bearing elements, when separately formed, may be secured in any preferred way,—as, by a shrinking-on or by the use of binding screws 264 upon kerfed bearing elements; motion may be imparted 85 to the bearing coupling element 260, or its equivalent, by means such as an intermediate shaft section 265, shown as carried in a bearing 266 and as terminating in a coupling element 267; and, in case rotary motion is to be 90 received from a downwardly extending or other angularly disposed shaft 27', any desired system of intermediate gears and any suitable lubricating system may be employed 95 within the housing 220 or upon or within the bracket 218, or its equivalent.

For example, assuming the mentioned bracket 218 to include bearing elements 268, 269, a shaft section 270, extending therethrough, may be provided not only with a coupling element at 267', adapted to interfit with the mentioned coupling 267, but with a bevel gear 271,—a co-operating gear 272 being shown as carried by the shaft 27', extending through a suitable bearing 273. Oil ducts 100 are suggested at 274, 275 and 276; and an access opening is suggested at 277; but it will be obvious that details such as those last referred to are entirely optional and that the forward extension 240 of the indicator housing 220 must be provided with some additional lateral opening, such as that shown at 278 as opposite an opening 278' in the "feeler"-carrying bracket 100,—the openings here referred to being of sufficient horizontal extent 105 to permit desired movement of the arm 215, or its equivalent.

It will be understood that rotation of a reflecting surface of the mirror 219 is effective to produce, incidentally to the rotative advance of said reflecting surface, and according to the rate of such rotation, the appearance of an advancing spot or a straight or curved line of illumination upon the translucent element 224; and the distinctness 120 125 130

- of the effect referred to may be enhanced by the use of the mentioned colored screen 226, to provide a diffuse illumination of green or other color light, affording a background upon which the mentioned line of indication is clearly visible. A complete or partial hood (not shown) may be provided thereover; and it will be understood that said translucent element 224 may be provided
- 10 with any desired lines, graduation, legends, or other markings, for the purpose of aiding the eye in judging the angular disposition of any excess of material and the amount of such excess in any fly wheel or other work unit W.
- 15 The background color-diffusion screen 226 may advantageously be formed by inclosing a sheet of one of the colored silicate films that are currently obtainable between a sheet of paper and a sheet of transparent celluloid; the graph-receiving screen 224, when not photo-sensitive, may be formed from any one or more of a variety of suitably stiff translucent materials,—as, from a paper
- 20 chart removably placed between celluloid sheets; any tilting of the concave mirror 243 during rotation of the mirror 219 obviously causes the line or graph 278", Fig. 27, as produced by the reflected beam or ray of light,
- 25 to assume a curved form,—its curvature depending upon the amount and angular location of any unbalance in the work unit W; and each face of the mirror 219 repeats the described action,—the frequency of repetition being such as to produce the appearance of continuity. Unless the bracket 100, or another support for the "sensory" part of a suitable "feeling" organization, is so mounted and manipulable (by means not shown)
- 30 as to permit the same to be raised and lowered during "spinning" operations (for the purpose of ascertaining the level of intersection of the geometrical axis of arbor 43, or its equivalent, with an inclined axis of
- 35 "spinning",—such as may result from a dynamic unbalance, obvious when both ends of the arbor 43 are permitted to wabble) the faces 215', 215" of arm 215 need have only the limited vertical diameter implied by Fig.
- 40 26. The rulings and legends upon screen 224 may be empirically provided.

- or guide-engaging section 280a and a shaft-carrying section 280b of said drill-press bracket or block need not be pivotally connected but may be comprised in a single casting; and the use of a construction comprising an additional section 280c (secured to bracket 280 by means such as screws 281) and an interfitting guide 282 (secured to post 22 by means such as additional screws 283) should be regarded as dependent upon the importance that may be attached to the provision of means for vertical adjustment of block 280, or its equivalent,—to adapt the same to the drilling in units W, which differ in their vertical dimensions or breadth of face. But the shaft-carrying section 280b may, in any case, comprise not only a vertical guide 285, for a suitable drill spindle 284, provided with a rack 286 (said spindle including a drill-carrying lower section 287, having a splined or similar connection with drill shaft 32) but also a horizontal bore or passage 288, 288' adapted to receive (preferably with the interposition of bearing elements 289, 289') a shaft 290, including or carrying rack-driving pinion 291. Shaft 290 may carry, at its respective ends, a counter-weight attachment member, such as a winding-sheave 291, and the mentioned handle or drill-advancing bar 46.
- Assuming the body 280 to remain stationary, a rope, chain or other flexible element 292, shown as extending over pulleys 293 and 294, may carry a counter-weight 295, so opposing the action of gravity upon the spindle 285 as to facilitate the application and withdrawal of the drill point 45; and, if desired, the mentioned parts may also be provided with means affording guidance as to the depth to which said drill point descends.
- For example, the sheave 291 and a collar 296 being shown as respectively secured by screws 297 and 298, a floating graduated disc 299 may be interposed between collar 296 and an additional collar 300, the latter being shown as provided with a set of pins 301, resiliently forced against a surface 302 of disc 299; and said disc and an index-carrying abutment 303 may respectively be provided with a spring-advanced pin 304 and a corresponding socket 305,—which may be adapted to interfit whenever the zero of said scale comes opposite said pointer as a result of rotation of said shaft 290. Thus, assuming that a reading of the indicator 28 has called for the cutting of a single drill hole (say) two centimeters deep at (say) an angle of 25° from the assumed zero of a fly wheel W, before or after withdrawal of said pin (shown as resiliently advanced by a spring 306, but as manipulable by a head 307) wheel W may be grasped and so manually rotated, in its horizontal plane, as to give a reading of "25°" upon the scale 170 upon main shaft 29; and the drill point 45 being brought into

Drilling organization

- The character 280 is applied generally to a spindle-supporting drill-press bracket or block; and, unless for the purpose of obviating an occasional substitution of alternative drill-press blocks (to correspond with various angular positions that may be given to shaft 32, or its equivalent, while maintaining said shaft at a uniform radial distance from the mentioned idler shaft 118,—to permit boring at various radial distances from the axis of rotation of any work W, according to the diameter thereof) a post-engaging

contact with the fly wheel W, the disc 299 may be manually so rotated as to bring its "2" opposite an index mark or pointer 308. As the drill point is thereafter lowered, the disc 299 may rotate with shaft 290, the pin 304 being optionally held from entering socket 305 by means such as a cross-pin 304a, movable relatively to a slot 304b and adapted alternatively to engage a terminal surface 304c of a guide boss 304d,—integral with disc 299 and adapted to receive both pin 304 and spring 306. Thus the reading of the disc 299 may at all times indicate the amount remaining to be cut; and the actual upper surface of work constitutes, in each instance a level of reference. This may vary from job to job; and it will be obvious that features referred to need not be confined, in point of usefulness, to combinations so complex as those herein described. Alternative blocks 280 may be substituted to vary the radial distance at which drilling is done.

Chip remover

The operation of a mechanism so sensitive as that of the described "feeling" organization ought not to be jeopardized by a careless disposition of borings; and, although chip removing elements of various types might be employed, the present disclosure will include details of a simple and effective chip remover, suitable to be supported from some part of bracket 100 and to remain out of contact with the work W until, at the completion of a "spinning" operation, said work is depressed or elevated or engaged for drilling. In the illustrated chip remover, assumed to be capable of alternative uses, a chip box 310, shown as rectangular in cross-section, is shown as elongated toward a contracted end 311 into which extends an air jet tube 312 and as expanded in an opposite direction,—its enlarged end being connected with a receptacular or tubular element such as a wide hose 314 (which may lead to a waste box, not shown) and an adapter 315 being optionally interposed.

Upper and lower openings 316, 317 may snugly fit drill point 45, or its equivalent; and a work-engaging guard element, preferably in the form of a rubber, leather or similar cushioning closure, 318, may be replaceably retained by means such as clips or strips 319, 320; and the entire organization so formed, or its equivalent, may be yieldably supported from plate 100c by means such as an irregular plate 321, secured by screws 322,—interfiting guide elements 323, 324, being respectively secured to box 310 and to said plate, with compression springs 325 interposed.

A clearance being normally maintained below the cushioning closure element 318, it will be understood that such slight elevation of the work W as results from a shifting of the

handle 42 toward the left, to elevate work-levelers, may be sufficient slightly to compress springs 225 and to prevent escape of borings below the closure elements 318. The jet of air used may be sufficiently powerful to obviate all need for a concurrent application of suction to hose 314; and air may be supplied to tubing 312 (as also to the described arbor jack cylinder 70) from a usual air line (not shown).

Mode of control and cycle of operations

All main features of the present organization having been referred to, attention may now be recalled to the fact that the lever 34 is adapted particularly to the manipulation of the control shaft 31, during successive cycles of operation.

Lever 34 is shown as carried by a bearing bracket 327; and said bracket may include or support a legend-carrying and fixed sector 328, having a parti-cylindrical surface and adapted to co-operate with pointer 329 (shown as extending radially from the pivot 35 of lever 34) and/or a notched arcuate stop element 330,—the notches 331 of the latter being engageable by a spring-pressed pin 332, carried by said lever and serving yieldably to hold the same where set. The respective ends of the arcuate element 330 are shown 95 as provided with limiting abutments 333, 333'.

The lever-carrying sector 328 may display, upon one or more of its surfaces such words as "Dynamic", "Static", "Stop", "Load", and "Drill"; and the adjustment of parts above referred to, including the mentioned cams on shaft 31, is such as to assure positional and functional relationships substantially as indicated below:

With the pointer 329 at "Load".—The machine is ready to receive a fly wheel or similar unit W, both the upper set of rollers 206d, 207d, 208d (carried by the bracket 100) and the corresponding lower set (carried by the plate 100') are "open"; the clutch 111 is disengaged, and the brake valve 148 is closed, the brake being on.

A shifting of the work-positioning arm 42 to the right then causes the work-stopping dogs 52, 52' to rise sufficiently to engage a fly wheel W as the latter is advanced (without lifting) from conveyor rollers 49a onto the rollers 49 of block 21.

Elevation of jack-operating lever 44 may then cause arbor 43 to rise sufficiently to pick up and center fly wheel W from below and to facilitate a connection of arbor 43 with the "spinning" or main shaft 29.

Cams 92, 95, 97a, and 97b being so formed as to permit shifting of the main control lever 34 to bring pointer 329 opposite the legend "Spinning" only when arm 42 and lever 44 have been restored to their respective neutral or intermediate positions (withdraw-

ing dogs 53 and elevator socket 65 respectively from work W and from arbor 43) execution of the respective movements referred to may now place all parts in readiness for a 5 "spinning" of work unit W, to obtain an indication of what is herein termed "primary" unbalance.

With the pointer 329 at "Static".—The brake is off; the upper set of rollers 206d, 207d, 208d is open,—so freed as to function as a "feeling" organization for indicator 28; the lower set of like rollers, carried by lower plate 100', remains closed or inwardly "locked", to prevent wobbling of the lower 10 end of arbor 43; the clutch 111 is so engaged as to rotate shafts 29 and 27', to effect a spinning of the former (at, say, 500 R. P. M.) and a simultaneous indication of any unbalance,—the latter being read by the operative 15 and hereinafter referred to as "primary" unbalance. (The amplitude of observed oscillation is found to be substantially proportional to the unbalance; and the graph-displaying element 222 is assumed to have been 20 empirically ruled and provided with suitable legends.)

With the pointer 329 at "Stop".—Upon the obtaining of an indication of the location and amount of "primary" unbalance, a shifting 25 of the lever 34, to bring the pointer 329 opposite "Stop" disengages clutch 111; and also applies the brake, by closing valve 148, to bring all parts to rest with both sets of rollers 206d, 207d, 208d, in their inner or arbor-centralizing positions.

With the pointer 329 at "Drill".—If unbalance beyond a permissible tolerance has been indicated, the brake remaining so applied as to hold shaft 29 stationary and the 30 rollers of both sets remaining in their inner or locking positions, the work W may be manually so rotated, turning the arbor 43 and the shaft 29 therewith, as to bring the "heavy" side thereof (as previously revealed by indicator 28 during "spinning") directly under the drill point 45,—the reading on scale 170 being thereby brought into correspondence with the angle reading then given by said indicator. Pointer 329 being momentarily 35 brought to "Load", a shifting of the work-positioning arm 42 toward the left elevates the work-levelers or platen elements 56.

With the bringing of pointer 329 opposite "Drill", the clutch 111 becomes effective to 40 rotate drill shaft 32; and the depression of drill-advancing bar 46 results in a removal of excess metal at such a point and in such quantity as substantially to perfect the "primary" balance of work unit W,—the reading 45 on disc 299 being used to show when a predetermined depth has been obtained. Either a single hole or a symmetrical series of holes is thus provided, chips being removed, and one of the cams 97a, 97b, being effective to 50 block any inadvertent attempt at a further

"spinning" of work unit W in advance of a lowering of the work-levelers 56.

With the pointer 329 at "Dynamic".—A check as to depth and location of drilling being optionally run as the pointer 329 passes 55 to a position opposite the legend "Static", the shift to "Dynamic" maintains the clutch 111 in position to rotate shaft 29, the brake being off; and it also frees both the upper and the lower sets of rollers 206d, 207d, 208d in such 60 manner as to permit both ends of arbor 43 to wobble, producing, if so disposed, opposite eccentricities above and below an intermediate "node", or no-wobble level. The resultant reading of indicator 28 is hereinafter 65 referred to as "secondary" unbalance, and treated as "dynamic" in origin.

The pointer 329 may again be brought to "Stop" and then to "Drill",—operations 70 above referred to under "Drill" being then repeated. The arm 42 and lever 34 may both be shifted to "Load" position. The arbor jack comprising or supporting socket 65 is then raised by elevation of lever 44; chuck 63 is disconnected; and the jack is again lowered,—the cutting of any holes in the "lower" 75 surface of work W being subsequently effected, at convenience, either in the same machine or in any ordinary drill press.

In preparation for the insertion of a new 80 work unit W, the lever 34 may remain positioned at "Load", the described interlocking means being employed to prevent prematurity or false sequence of operation; and the described cycle may be repeated at a rate of 85 (say) thirty fly wheels per hour, as against about five fly wheels per hour by old methods,—only about one quarter of the former 90 space being required.

The tolerance permitted to any "secondary" unbalance, assumed to be mainly "dynamic" in origin, may be about ten times greater than the tolerance for "static" or "primary" unbalance,—only a relatively small component of "dynamic" unbalance being effective to produce roughness in the 100 operation of an engine fly wheel, as ordinarily constructed and employed.

Since that indicator reading which is obtained when control lever 34 is set at "Static" 105 (the lower end of arbor 43 being then restrained) may result, in part, from "dynamic" unbalance, the expression "primary" unbalance is herein employed. It will be evident that the tendency of some couple to produce an inclination of the axis of rotation, about what may be termed a nodal or no-wobble level or point somewhat remote from the plane of the lower set of rollers 110 206d, 207d, 208d, may escape detection during "spinning" with the pointer 329 at "Static"; and the effect of this suggested couple, when such exists, may be either enhanced or diminished by the described correction for "primary" unbalance,—correction 115 120 125

for the latter giving a straight-line graph upon indicator 28. The term "secondary" unbalance is accordingly herein applied to such unbalance (whether "static" or "dynamic" in the sense these words have heretofore been understood) as can be ascertained by a "spinning" of a work unit, with both ends free to wobble, after correction for so-called "primary" unbalance has been effected.

As indicated, in actual practice, and in order that the "secondary" correction shall not defeat the "primary" correction, it is found best to treat the latter as if it were entirely "dynamic" in origin,—any necessary correctional removals of metal being, in this instance, effected respectively in the upper and the lower surfaces of a unit and at diametrically opposite points near the periphery thereof. That is to say, (all parts being empirically standardized and calibrated) if a "dynamic" reading seems to call for two borings to a depth of (say) $\frac{1}{16}$ of an inch, by a $\frac{1}{2}$ inch drill, one such boring may be effected in the upper surface, at the indicated angle, the other being subsequently effected, in the lower surface of the unit, at an angle of 180° from the first,—and preferably in a separate drill press.

Although the foregoing description has included but one illustrative embodiment of the present invention, it should be understood not only that numerous features thereof are believed to be capable of independent use but that numerous modifications thereof might easily be devised, by workers skilled in the arts to which this case relates, without involving the slightest departure from the spirit and scope of this invention,—as the same is indicated above and in the following claims.

40 I claim:

1. In a machine suitable for use in the balancing of work units of fly-wheel type: a non-rotary work support for said units; a work-centering arbor of such length as to be capable of depression below the top of said support and means for rotating said arbor while permitting thereto eccentric motion corresponding to unbalance in said unit.

2. In a machine suitable for use in the balancing of work units of fly-wheel type: a work-centering arbor; means for initially supporting said units independently of said arbor; means for advancing said arbor through said supporting means; means for rotating said arbor; and means for so positioning said arbor as to permit substantially horizontal reception and removal of said units relatively to said supporting means.

3. In a machine suitable for use in the balancing of work units of fly-wheel type: non-rotary means for supporting said units; means for raising said unit therefrom; means for spinning said units; means for indicating, in the form of a graph, any eccentricity

of rotation due to unbalance during such spinning; and means for partially correcting such unbalance before finally removing said unit from said supporting means.

4. In a machine for balancing units provided with hubs: a standardized arbor adapted to be advanced and retracted through the hubs of successive units and to be engaged during rotation of said units by wobble-limiting means near its respective ends; rotating means; wobble-limiting means movable to and from said arbor ends; means for simultaneously indicating the location and the amount of any unbalance tending to produce wobble at one of said ends; and means for advancing and retracting said arbor.

5. In a balancing machine: a work-support provided with work-leveling means; a work-centering arbor; means for rotating said arbor; and means for so moving one of said means as to separate said work from said arbor at times when said arbor is not rotated.

6. In an indicator suitable for use in determining unbalance: a housing; a rotatable mirror; an oscillatable mirror so mounted as to reflect light from a suitable source thereto; means for oscillating said oscillatable mirror during rotation of said rotatable mirror; a source of light; a graph-receiving element positioned to receive light reflected by said mirrors; and a color screen interposed between said source of light and said graph-receiving element. 95

7. In an indicator suitable for use in determining unbalance: a housing; a rotatable mirror; an oscillatable mirror so mounted as to reflect light from a suitable source thereto; means for oscillating said oscillatable mirror during rotation of said rotatable mirror; a source of light; said housing being provided with a removable section and one of said mirrors being supported by means which are insertable upon removal of said section. 100

8. In a balancing machine: means for so supporting and rotating a body to be balanced as to permit an eccentric movement thereof in response to unbalance therein; means for revealing such eccentric movement by a graph; means for correcting such unbalance; and means for transmitting power alternatively to said rotating means and to said correcting means. 110

9. In a machine of the general character described: a gear box containing a lubricating oil; a clutch; a shaft adapted to be driven through said clutch; a gear pump comprising a part upon said shaft; a valved outlet from said gear pump, provided with means for delivery of oil to mentioned parts requiring lubrication; and means for so manipulating the valve, in said outlet as to render said gear pump and said valve together operative for a braking effect when said 125

130

clutch is so shifted as to discontinue rotation of said shaft.

10. In a balancing machine: a work-spinning shaft, a drill shaft extending parallel therewith; means for alternatively rotating said shafts; and means for so supporting one of said shafts as to permit variation in the distance between the axes of said shafts.

11. In a balancing machine: a base; work positioning and supporting means carried by said base; a post extending above said base and carrying a gear box; gearing in said box; a work-spinning shaft; a drill shaft and a cam shaft extending downward from said gear box; means for alternatively rotating said work-spinning shaft and said drill shaft through said gear; means for indicating any eccentricity of movement of said work, due to unbalance, during spinning thereof; and means for so manipulating said cam shaft as to discontinue rotation of said work-spinning shaft and to rotate said drill shaft to correct said unbalance.

12. In a balancing machine: work holding means; a motor; means for so rotating therefrom work to be balanced as to permit eccentricity of movement proportional to unbalance in said unit; means for substantially removing any unbalance while so holding said unit as to render the rotational axis and the geometrical axis thereof substantially coincidental.

13. In a balancing machine: means for spinning a work-unit by permitting a limited wobbling therefrom in consequence of unbalance therein; means revealing the amount and angular location of such unbalance; means for stopping said spinning, to permit a rotative shifting of said unit to a position for correcting such unbalance; means for indicating the attainment of such position; and means for such correction.

14. In a balancing machine: work positioning means; work spinning means; and means rendering the operation of one of said means conditional upon the previous operation of the other of said means.

15. In a balancing machine: a control shaft provided with means for its partial rotation to positions respectively favorable to a loading of units, to a spinning thereof for the ascertainment of unbalance, to a stopping thereof, and to a correction of any unbalance in said units; and respective means for effecting such loading, spinning, stopping and correction of unbalance upon the rotation of said shaft to said positions in sequence.

16. In a balancing machine: a control shaft provided with means for its partial rotation to positions respectively favorable to the loading of units, to a spinning thereof for the ascertainment of unbalance, to a stopping thereof and to a correction of any unbalance in said units; and means for effecting 35 mechanical operations for the correction of

unbalance upon the rotation of said shaft to said positions in sequence,—said shaft being provided with means for its manipulation by a lever and said lever being provided with means for indicating the rotative position of said shaft.

17. In a balancing machine: means for ascertaining unbalance in a work unit; means for supporting said unit during correction of unbalance; means for effecting such correction; and a chip remover provided with means to render the same substantially inoperative during the operation of said ascertaining means but operative upon elevation of said supporting means.

18. In a balancing machine: means for rotating a work unit; means for ascertaining unbalance in the work unit while rotating the same; coaxial means for supporting said unit during correction of unbalance; and means for effecting such correction.

19. The method of balancing units of the flywheel type which consists in spinning the unit, mounted on a suitable shaft, with one end held and the other end free, correcting the unbalance indicated by changing the mass at one point along the unit, thereby obtaining approximately static balance, spinning the unit with both ends free, and correcting the indicated unbalance by changing the mass at one side of the unit in an amount sufficient to correct one-half of the indicated unbalance, and changing the mass at the other side of the unit and at a diametrically opposite point in an amount sufficient to correct the other half of the indicated unbalance, thereby removing the disturbing couple without affecting the approximate static balance obtained by the first correction.

20. The method of correcting unbalance in units of the flywheel type which comprises rotating the unit with one end held and the other end free, observing the amount and direction of eccentricity of the movement performed by the free end of the unit, correcting the unbalance indicated by changing the mass at one point along the unit thereby obtaining approximately static balance, spinning the unit with both ends free, observing the amount and direction of eccentricity of the movement performed by a free end of the unit, and correcting the indicated unbalance by changing the mass at one side of the unit in an amount sufficient to correct one half of the indicated unbalance, and changing the mass at the other side of the unit and at a diametrically opposite point in an amount sufficient to correct the other half of the indicated unbalance, thereby eliminating the disturbing couple without affecting the static balance.

21. In a balancing machine for apertured work, the combination of a work centering arbor, means for inserting the arbor through the work and in driving relation thereto, and

70

130

means on the other side of the arbor for engaging and rotating the arbor to determine the state of balance of the work.

22. In a balancing machine for apertured work, the combination of a work supporting platform, a supporting shaft for the work normally below the platform, means for inserting the shaft upwardly through the aperture in the work supported on the platform and elevating the shaft and support above the work support, means for gripping the shaft and holding it in suspended relation, means for retracting the shaft elevating means, and means for spinning the shaft to determine its state of balance.

23. In a balancing machine for apertured work, the combination of a work supporting platform, a supporting shaft for the work normally below the platform, work centering devices, means for projecting said devices in position to engage and center the work, means for inserting the shaft upwardly through the aperture in the work supported on the platform and elevating the shaft and support above the work support, means for gripping the shaft and holding it in suspended relation, means for retracting the shaft elevating means, means for retracting the work centering devices, and means for spinning the shaft to determine its state of balance.

24. A balancing machine for heavy objects comprising a supporting stand forming part of a conveyor arranged to feed unbalanced objects to the machine and to return balanced objects thereto, means arranged to be projected above the stand and to engage the object and elevate it above the stand, means for spinning the object when so elevated to determine its unbalance, and means for lowering the object upon the stand upon completion of the balancing operation, to permit its discharge on to the conveyor.

In testimony whereof I affix my signature.

45 THOMAS C. VAN DEGRIFT.
